UNITED STATES PATENT OFFICE.

GEORGE A. CARRERAS, OF ST. LOUIS, MISSOURI.

CABLE-GRIP.

SPECIFICATION forming part of Letters Patent No. 405,145, dated June 11, 1889.

Application filed February 27, 1889. Serial No. 301,380. (No model.)

To all whom it may concern:

Be it known that I, GEORGE A. CARRERAS, of the city of St. Louis, in the State of Missouri, have invented a certain new and useful 5 Improvement in Cable-Grips, of which the following is a full, clear, and exact description, reference being had to the accompanying drawings, forming part of this specification, and in which—
10 Figure I is a side elevation of my improved grip. Fig. II is an edge view. Fig. III is a detail transverse section taken on line III III, Fig. I. Fig. IV is a detail vertical section taken on line IV IV, Fig. I. Fig. V is a similar view taken on line V V, Fig. I. Fig. VI is a detail side view showing the jaws open. Fig. VII is a detail edge view showing the jaws open and modified.

My invention relates to an improved grip 20 for street-cars; and my invention consists in features of novelty hereinafter fully described, and pointed out in the claims.

Referring to the drawings, 1 represents a U-shaped frame, to the lower end of which the upper jaw 2 is secured.

3½ represents a die dovetailed into the upper jaw.

Fitting and sliding within the frame 1 are plates 3 and 4, secured together by bolts 5. 30 To the lower end of the plate 3 the lower jaw 6 is secured by means of rivets or bolts 7, and into this jaw a die 8 is dovetailed.

As shown in Fig. II, the plate 3 passes upward through the center of the upper jaw 2, and there is preferably a die 3½ on each side of the jaw 2 and a corresponding die 8 on each side of the jaw 6. In this way the grip may take the cable 9 on either side.

In Fig. VII, I have shown a single instead 40 of a double grip, or a grip having dies on one side of it.

11 represents a cross-head through which the upper plate 4 passes, and which is secured to the frame 1 by means of two pairs of bolts 45 12 on each side of the grip.

The frame 1 is divided, as shown by dotted lines 13. Secured to the center of the cross-head is a strap 14, in which the lower end of a screw 15 is stepped, as shown in Figs. I and 50 IV. The screw passes up to and through a cross head or bar 16, secured to the upper end of the plate 4, and it also passes upward and

through the frame 1, and has above the frame a fixed collar 16' and below the frame a fixed collar 17. On the upper end of the 55 screw is a hand-wheel 18. It will thus be seen that as the screw is turned in the proper direction the lower jaw will be made to approach the upper jaw to grip the cable, as shown in Fig. I, and when the screw is turned in the 60 other direction the jaw is thrown down to release the cable. It may be moved down only sufficiently to relieve the cable, or it may be thrown down as far as shown in Fig. VI, for the purpose of getting beneath and picking up 65 the cable.

On the screw 15 is a ratchet-wheel 19, engaged by one end of a pawl 20, pivoted at 21 to the frame 1. To the outer end of the pawl 20 is secured the upper end of a rod 22, the 70 lower end of which is made fast to a foot-lever 23, pivoted at 24 to the frame. The rod passes through a bracket 25, secured to the frame 1, and it has on it a fixed collar or shoulder 26. Between the shoulder 26 and the bracket 25 75 is placed a spring 27. The action of this spring is to hold the pawl into engagement with the ratchet, so that the jaws may be held firmly against the cable in running long 80 distances without keeping hold of the hand-wheel 18, the screw being prevented from turning by means of the pawl and ratchet. If it is not desired to use the pawl and ratchet, the former may be held out of engagement 85 with the latter by means of a pin 28 passing through a hole 29 in the pawl and a hole 30 in the frame 1.

The entire grip is mounted by means of journals or arbors 31 in boxes 32, secured in any well-known manner to the car. By thus mounting the grip it is capable of being swung laterally or in a horizontal plane for the purpose of bringing its jaws into contact with the cable, which may be swung a little to one side of the jaws when said cable diverges from 95 the straight line.

For the purpose of holding the grip in a vertical position and yet permitting it to be swung horizontally, when desired to take hold of the cable, as described, I use a sliding dog 100 or bar 34, secured to the frame 1 by means of strips 35, and engaging at its lower end a notched strip or plate 36. (See Fig. II.) Secured to the upper end of the bar or dog is a

spring hand-piece 38. It will thus be seen that by pressing inwardly on the handle 38 the dog will be raised out of engagement with the notches of the plate 36, and the grip is then capable of being swung in a horizontal plane for the purpose mentioned. Then, by bringing it back to a vertical position and allowing the dog or bar to enter the central notch on the plate 36, the grip will be held in its vertical position.

In some cable roads the conduit does not extend into the car stables or sheds, so that it becomes desirable to remove the grip from the conduit to permit the car to be run into the shed. For this purpose I divide the frame 1 by means of the cross-head 11 and bolts 12, as stated, and the plates 3 4 are provided instead of making a single plate. The plates 3 4 are connected by the bolts 5, as stated. Now, by removing one pair of the bolts 12 on each side of the grip and by removing the bolts 5 it will be seen that the lower part of the grip will be separated from the upper part, and may be taken out through the usual well, while the car, carrying the upper portion of the grip, can be run into the shed.

For the purpose of forming turning-bearings for the cable when not held firmly by the jaws, I journal outer rollers 40 and a central roller 41 to each end of the upper jaw 2, these rollers being preferably made conical and extending down beyond the line of the cable when engaged by the jaws. These rollers are placed vertical, and are simply held to the jaw by means of stems 42 thereon passing through the jaw and held therein by keys 43. This is shown plainly in Fig. II. On the lower jaw 6 are journaled pulleys 44, to support the cable vertically when not firmly grasped by the jaws.

45 represents a roller journaled in the bottom of the lower jaw, to receive the impact of any obstruction against which the grip might come in contact.

45 The pulleys 44 are set one-eighth of an inch above the lower die, in order to carry the cable free of said die when the dies are not in contact and the grip is open.

I claim as my invention—

1. A cable-grip provided with arbors, journal-boxes in which the arbors fit, and a dog and notched plate for holding the grip in a vertical position, but permitting it to be swung on a horizontal plane, substantially as and for the purpose set forth. 50

2. In a cable-grip, the combination of the frame 1, upper jaw secured to the frame, plates 3 4, and lower jaw secured to the plate 3, the frame 1 being divided and connected by a cross-head and bolts, substantially as and for the purpose set forth. 55

3. In a cable-grip, the combination, with the frame and the upper jaw secured to said frame, of the sliding plates, the lower jaw carried by said plates, a cross-head attached to 65 said plates, and an upright screw stepped in said cross-head for raising and lowering said lower jaw, substantially as set forth.

4. In a cable-grip, the combination of the frame, an upper jaw carried by the frame, 70 sliding plates, lower jaw carried by the plates, a screw for operating the plates, a ratchet secured to the screw, and a spring-pawl for engaging the ratchet, substantially as and for the purpose set forth. 75

5. In a cable-grip, the combination of the frame, upper jaw secured to the frame, sliding plates, and lower jaw secured to the plates, a screw for raising and lowering the plates, ratchet-wheel secured to the screw, 80 pawl engaging the ratchet-wheel, a rod secured to the pawl, a lever pivoted to the frame and to which the lower end of the rod is secured, a spring 27, for forcing the pawl into engagement with the ratchet, and a pin 28, for holding the pawl out of engagement with the ratchet and against the action of the spring, 85 substantially as and for the purpose set forth. 85

6. In a cable-grip, the combination of the upper and lower jaws, rollers 40 and 41, secured 90 to the upper jaw, and rollers 44, secured to the lower jaw, substantially as and for the purpose set forth.

GEORGE A. CARRERAS.
